LOADER

Lynn Jones and Guy Blake, Indianola, Iowa, assignors, by mesne assignments, to New Method Equipment Company, a corporation of Iowa

Application November 15, 1941, Serial No. 419,311

7 Claims. (Cl. 214—139)

The principal object of this invention is to provide a loader that may be secured to a tractor or the like, that is light in weight, efficient in operation and positive in action.

A further object of our invention is to provide a loader having a scoop or shovel portion thereon that will, when in operation, receive a straight thrust from the rear axle of the tractor for a greater power and one which utilizes the inclined plane principle for hoisting the loaded scoop, thereby requiring a minimum of power for the raising operation.

A still further object of this invention is to provide a loader which may be tripped for unloading at any desired elevation and which will automatically return to an operable or pick-up position when lowered.

A still further object of this invention is to provide a loader that is extremely economical in manufacture, durable and efficient in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a side elevational view of our loader secured to a tractor and in a semi-raised position.

Fig. 2 is an enlarged top plan view of the forward portion of the loader mechanism and scoop.

Fig. 3 is an enlarged front cross sectional view of the loader taken on line 3—3 of Fig. 2 showing the structure of the slide-lift mechanism.

Fig. 4 is an enlarged side cross sectional view of the dump scoop latch assembly mechanism and is taken on line 4—4 of Fig. 2.

Fig. 5 is an enlarged front elevational view of the winch and drive assembly of the loader mechanism.

Fig. 6 is an enlarged side elevational view of the scoop element in a dumped position.

Fig. 7 is an enlarged front elevational view of the latch assembly showing the adjustable latch plate.

Fig. 8 is an enlarged side elevational view of the winch-drive assembly.

Fig. 9 is an enlarged perspective view of the head portion placed on top of the vertical guide tracks for permitting an addition to the top of the vertical guide tracks.

Heretofore loading mechanisms have been of generally a type such as the steam shovel, or

the common hand-operated loading scoops. These types were difficult to use and did not lend themselves well to all-around use, being only good for large operations or for removing dirt or the like. These scoops did not aid a farmer in the everyday problems arising for the removal of dirt, for trenching, for loading manure and the like, and they required ready-cut dirt by not having sufficient power, or by not being efficient enough to cut their own path for the loading of material onto the scoop or container. We have overcome such disadvantages as will hereinafter be more fully set forth.

Referring to the drawings, we have used the numeral 10 to indicate a tractor having the rear wheels 11 and rear axle 12 as shown by dotted lines in Fig. 1 of the drawings. It is to such a vehicle that we attach our device which we will now describe. The numerals 13 and 14 indicate two vertical guide track bars parallel to each other and secured to the frame of the tractor through the medium of the beams 15 and 16 respectively. The numerals 17 and 18 indicate two vertical slides capable of slidably engaging the track members 13 and 14 and having secured thereto a horizontal cross beam 19 as shown in Fig. 3 of the drawings. These slide members 17 and 18 are further braced by the beams 20 and braces 21. On either end of the beam 19 are the hanger members 22 and 23 having rotatably mounted in the lower portion thereof the rollers 24 and 25 respectively. This whole assembly is capable of sliding on the vertical track members 13 and 14. The numerals 26 and 27 indicate two beams each having their rearward ends pivotally secured to the axle 12 of the tractor 10 through the medium of the bearing members 28 as shown in Fig. 1. These beams extend through the hangers 22 and 23 respectively, and are supported by the rollers 24 and 25 respectively. Pivotally secured to the forward ends of the beams 26 and 27 is a scoop or shovel 29 which may be fitted with tines 30 or a shovel bottom portion 31. This shovel bottom portion 31 may be extended by the use of removable plates or the like 32 as shown by dotted lines in Fig. 2 of the drawings. Rigidly secured to the rearward portion of the scoop 29 is a latch bar or like 33. The numeral 34 indicates a lever member rigidly secured to the rearward end of the scoop 29, whose function will hereinafter be described. We have used the numeral 35 to indicate a latch hanger pivotally secured to a cross beam 36 which extends between the channel brace members 26 and 27.

This latch mechanism has thereon an adjustable plate element 37 which may be vertically adjusted, and which is capable of receiving the latch bar 38 when the scoop is in a normal operative position. The numeral 38 indicates a slide-way rigidly secured to the side of the member 35 and capable of receiving an operating lever 39 as shown in the drawings. This operating lever is secured to a shaft 40, which in turn is rotatably supported on the beam 36, extends outwardly to a point adjacent the side beam 27 and has a lever 41 secured to its outer end. This lever is held in one direction by means of the spring 42 and has secured to its outer end a rope, cable or like 43 for permitting the operator to release the latch 35 and permitting the scoop member to drop down, thereby depositing its load. We have used the numeral 44 to indicate a head plate capable of being detachably secured to the upper ends of the vertical guide tracks 13 and 14 and having mounted thereon a pulley wheel 45, an arm 46, and an arm 47 as shown in Fig. 9, of the drawings. The numeral 48 indicates a chain, cable or like having one end secured to the lever member 34, passing downwardly and around the beam 36 through a suitable housing and thence passing upwardly and having its other end secured to the lower portion of a tension spring 49. The other end of this tension spring 49 is secured to the arm 47. The numeral 50 indicates a stop plate capable of being placed on any one of the lengths of the chain 48 and provides a stop when the chain has reached a pre-determined position.

By this structure, when the scoop 29 is in a raised position, and the rope 43 is pulled, the latch member 35 will disengage the latch bar 38, permitting the scoop to empty its load and assume the position shown in Fig. 6 of the drawings. As the beams 26 and 27 are lowered, the chain member 48 will again pull the scoop 29 to such a position that the latch bar 38 will engage the hole in the plate 37 for retaining the scoop in its normal position.

To provide the functioning means for the device, we have provided a winch assembly which will be described. The numeral 51 indicates a frame member secured to the rearward portion of the vertical guide rails 13 and 14 as shown in Fig. 5. The numeral 52 indicates a pulley wheel capable of being operated by the power take-off of a tractor through the medium of a belt or the like. This pulley wheel is rigidly secured to a shaft 53 which is rotatably mounted in the frame 51. The numeral 54 indicates a friction wheel rigidly secured to the shaft 53 within the frame 51. I have used the numeral 55 to indicate a shaft having one end rotatably mounted in the frame 51 and its other end extending through a vertical slot 56 and rotatably secured to a lever member 57 as shown in Fig. 8 of the drawings. This lever member has one end pivoted to the frame 51, and its other end extending upwardly and having an operating bar 58 secured to its upper end, which extends back to a point adjacent the driver of the tractor for moving the axle or shaft 55 upwardly or downwardly. The numeral 59 indicates a transmission wheel capable of contacting and being operated by the friction wheel 54, when the lever 57 has moved one end of the shaft 55 to a downward position, thereby causing the wheel 59 and shaft 55 to rotate when power is applied to the pulley wheel 52. Supported on a cross arm 60 is

a brake shoe 61 capable of contacting and holding the transmission wheel 59 when the lever 57 is moved, so that the end of the shaft 55 is in a raised position. When the shaft 55 is in a raised position, the transmission wheel 59 is out of engagement with the friction wheel 54. The numeral 62 indicates a sprocket gear rigidly secured to the shaft 55. The numeral 63 indicates a winch or drum mounted on an axle or shaft 10 which is rotatably supported in the frame 51. The numeral 64 indicates a sprocket wheel secured to the winch-drum assembly, permitting this drum to be operated by a chain 65 which extends over the sprocket gear 62 and 64. The numeral 66 indicates a cable having one end secured to the drum 63, extending up and over the pulley member 45 on the top member 44, thence downwardly and about a pulley wheel 67 rotatably mounted on the beam 19, and thence upwardly to the arm 46. The numerals 68 indicate guide members secured to the beam 19 for preventing the displacement of the cable 67. Thus, when power is applied to the pulley wheel 52 and the lever 57 is moved, so that the wheel 59 is in contact with the friction wheel 54, the drum 63 will be rotated, thereby winding the cable about the drum and pulling the slide member or cross beam 19 upwardly. This raises the forward ends of the beams 26 and 27, thereby raising the scoop member 29 to its upper position. As the lever 57 is moved in the other direction, the transmission wheel 59 will be out of engagement with the friction wheel 54, permitting the weight of the scoop 29 to lower the whole assembly 35 until the lever 57 is moved further in its forward direction, which permits the wheel 59 to contact the brake shoe 61, thereby permitting the slowing down or stopping of the scoop assembly at any point of its elevation.

40 The practical operation of our device is as follows:

The beams 26 and 27 are secured at their rearward ends to the pivotal connection 28, and the beams 15 and 16 are secured to the tractor. 45 These beams are then lowered to the ground so that the scoop portion 29 is adjacent to or touches the earth or the material to be loaded. The tractor is then run forwardly picking up the material, and when the scoop 29 is loaded, the operator will pull rearwardly on the rod 58, putting the transmission wheel 59 in contact with the friction wheel 54, thereby operating the winch 63, which, through the medium of the cable 66, will pull upwardly on the beam 19, causing the slides 17 and 18 to slide upwardly on the vertical guides 13 and 14 respectively to a position such as shown in Fig. 1 of the drawings. The operator then pulls on the cable or cord 43, thereby pulling the latch plate 37 out of engagement with the latch bar 38 and permitting the scoop to dump by virtue of the load carried therein to a position as shown in Fig. 6 of the drawings. If the scoop is in its extreme top position or thereabouts, the plate 50 65 will prevent the chain from going too far through the tunnel loop on the beam 36. To lower the device to its operating position, it is then merely necessary to push forwardly on the rod 58 so that the transmission wheel 59 is out of engagement with the friction wheel 54. The weight of the scoop assembly and latching mechanism will cause the whole assembly to drop until the chain 48 tightens, thereby pulling the scoop back to its normal operating position and forcing the latch bar 38 into a locked position within

the hole in the plate 37. The assembly 35 has been returned to position by the spring 42 when the cable 43 is released by the operator. The entire assembly can be stopped at any point of its downward movement by pushing forwardly on the rod 58, thereby bringing the transmission wheel 59 into engagement with the brake shoe 61 and stopping the entire action. While the assembly is being raised, the beams 26 and 27 ride on the rollers 24 and 25, and the pulley wheel 52 is operatively connected to the power take-off of the tractor through a belt or like. By providing the cross beam 19, guide tracks 17 and 18, and the brace rods 20 and 21, the entire assembly is made rigid with a minimum of weight. The transmission assembly between the power take-off and the winch drum needs only one control to provide the functions of a power driven shaft, a free running clutch, and a brake assembly all within a forward and rearward movement of the rod 58.

When it is desired to extend the height of the assembly, it is merely necessary to add an additional section of guide track 13 and 14 to the upper end. Sufficient cable 66 can be carried on the drum 63 to anticipate such an extension, and the member 44 can be placed on top of the added section to provide the arms 46 and 47 and pulley wheel 45. By using an angular top rail with the vertical guide sections and by using angular supports on the beam 44, the whole device will be centered and held rigidly on the top of the vertical guide tracks.

Thus, it will be seen that I have provided a loader which fulfills all of my objects and presents many more obvious advantages. The device is versatile in its many adaptations, is easily placed on or removed from a tractor, has but two controls to operate, and will perform the function of a power scoop or loader, a carrier and any other operations of a similar nature. The device possesses great power, is extremely light in weight, and is readily adaptable to changing conditions or types of work. In this connection, the latch plate 37 may be adjusted to provide any desired angle to the forward portion of the scoop 29 and obviously any type of scoop or shovel may be employed in place of the type we have shown.

Hereinafter, the assembly shown in Fig. 3 of the drawings and consisting of the guides 17 and 18, the beam 19, cross braces 20 and 21, hangers 22 and 23, and rollers 24 and 25 will be referred to as the carrier. The friction clutch arrangement 59, winch 63, friction wheel 54, and attendant mechanism will hereinafter be called the winch operating mechanism. The loader, scoop or shovel assembly 28 will hereinafter be referred to as a bucket element. The chain element 48, spring 49 and plate 50 will hereinafter be called a bucket returning means.

Some changes may be made in the construction and arrangement of our improved loader without departing from the real spirit and purpose of our invention, and it is our intention to cover by our claims any modified forms of structure or use of mechanical equivalents which may be reasonably included within their scope.

We claim:

1. In a loader, a beam element having its rearward end pivotally secured to the rear axle of a tractor, a vertical guide track secured to the forward portion of the tractor, a carrier member consisting of a cross bar operatively mounted on said guide track and having hangers capable of operatively engaging said beam element, a bucket

element pivotally secured to the forward end of said beam, an engaging means operatively secured to said beam, a latch bar on said bucket capable of being engaged by said engaging means at times, a means for manually disengaging said engaging means from said latch bar at times, a winch mechanism operatively secured to said vertical guide element and having a drum thereon, a cable operatively secured to said drum extending through a pulley adjacent the top of said vertical guide element and having its other end secured to said carrier member, a means for operatively selectively connecting said winch mechanism to the power take-off of a tractor by means of a manual control, and a bucket return mechanism including a lever on the bucket and a flexible member and spring secured to the lever and to a stationary part of the loader to cause the bucket to return to loading position when lowered, the bucket return mechanism being capable of returning said bucket so that said latch bar is in engagement with said engaging means when said beam element is lowered by said carrier after said bucket has been released from said engaging means.

2. In a device of the class described, a vertical guide track secured to the forward end of a tractor or like, a carrier mechanism consisting of a cross bar slidably mounted on said vertical guide track, hanger members on said cross bar, a beam element pivotally secured to the tractor to the rear of said vertical guide tracks and operatively engaged by said hanger members on said carrier, a scoop element pivotally secured to the forward end of said beam forwardly of said hanger element, a winch assembly secured to said vertical guide track in operative engagement with the power take-off of a tractor, a transmission assembly, a means for manually selectively engaging said transmission assembly to said winch drum assembly at times, a cable operatively mounted on the drum of said winch assembly extending up and over the end of said vertical guide track and having its other end secured to said cross bar for permitting the raising of said cross bar on said vertical guide track when said winch drum assembly is connected through the transmission to the power take-off of a tractor, a latch mechanism operatively mounted on said beam and capable of holding said scoop element in rigid alignment at times, means for manually disengaging said latch mechanism from said scoop for permitting said scoop to pivot at times, and a return mechanism having one end operatively secured by spring means to said vertical guide track and its other end secured to said scoop element through a fixed pulley for returning said scoop element into engagement with said latch element while said beam and said scoop are being brought to a lowered position by said carrier.

3. In a device of the class described, a vertical guide track secured to the forward end of a tractor or like, a carrier mechanism slidably mounted on said vertical guide track, hanger members on said carrier, a beam element pivotally secured to the tractor to the rear of said vertical guide tracks and operatively engaged by said hanger members on said carrier, a scoop element pivotally secured to the forward end of said beam forwardly of said hanger element, a winch assembly secured to said vertical guide track in operative engagement with the power take-off of a tractor, a transmission assembly, a means for manually selectively engaging said transmission assembly to said winch drum assembly at times,

a cable operatively mounted on the drum of said winch assembly extending up and over the end of said vertical guide track and having its other end secured to said carrier for permitting the raising of said carrier on said vertical guide track when said winch drum assembly is connected through the transmission to the power take-off of a tractor, a latch means secured to said scoop element, an engaging means operatively mounted on said beam, an adjustable catch element on said engaging means capable of contacting said latch assembly on said scoop for holding it in rigid alignment at times, an operating lever secured to said engaging means for permitting the manual disengagement of the engaging means from said latch assembly, a means for yieldingly returning said engaging means to an operating position, and a means for returning said scoop element to a position where it will be engaged by said engaging means when said beam and said scoop are brought to a lowered position.

4. In a device of the class described, a vertical guide track designed to be secured to the forward portion of a tractor, a carrier mechanism operatively mounted on said vertical guide track, beam members having their rearward ends pivotally secured to the rear of a tractor and capable of being raised by said carrier at times, a bucket scoop operatively secured to the forward end of said beam members, a winch assembly secured adjacent said vertical guide tracks and comprising, a friction wheel capable of being operatively connected to the power take-off of a tractor, a transmission wheel rotatably mounted adjacent said friction wheel, a lever member pivotally secured to the shaft of said transmission wheel, a brake shoe adjacent said transmission wheel, a drum element in operative engagement with said transmission wheel, and a cable having one end secured to said drum element and the other end in operative engagement with said carrier; said transmission element being placed in engagement with said friction wheel when said lever member is moved in one direction being out of engagement with said friction wheel when said lever is in a neutral position and said transmission wheel being braked by said brake shoe when said lever is in its other extreme position for controlling the movement of said drum.

5. In a device of the class described, a vertical guide track designed to be secured to the forward portion of a tractor, a carrier mechanism operatively mounted on said vertical guide track, beam members having their rearward ends pivotally secured to the rear of a tractor and capable of being raised by said carrier at times, a bucket scoop operatively secured to the forward end of said beam members, a winch assembly operatively secured adjacent said vertical guide tracks

and selectively operatively engaging the power take-off of a tractor, a means connecting said winch assembly to said carrier for moving said carrier on said vertical guide tracks, a means

5 for rigidly securing said bucket scoop in position relative to said beam members at times, a lever for manually disengaging said securing means for permitting said bucket scoop to pivot on said beams at times, and a return mechanism consisting of a lever on the bucket scoop and a flexible member anchored to the tractor capable of returning said bucket into engagement with said securing means when said carrier is brought to a lowered position.

10 6. In a device of the class described, a vertical guide track designed to be secured to the forward portion of a tractor, a carrier mechanism operatively mounted on said vertical guide track, beam members having their rearward ends pivotally secured to the rear of a tractor and capable of being raised by said carrier at times, a bucket scoop operatively secured to the forward end of said beam members, a transmission element adjacent said vertical guide members and capable of being selectively engaged by the power take-off of a tractor at times, a means 15 for operatively securing said transmission element to said carrier for permitting said carrier to be raised on said vertical guide tracks when said transmission element is in operative communication with the power take-off of a tractor, a means for releasing said transmission at times, a releasable latch mechanism for securing said bucket scoop in rigid alignment with said beams 20 at times, a removable cross head on the top of said vertical guide track, and a means connected at one end to said cross head and at the other to said bucket scoop for returning said bucket scoop to a latched position when said beams are lowered by said carrier.

25 7. In a tractor mounted loader, a side frame secured to the sides of the tractor and extending forwardly therefrom, a vertical frame secured to the forward end of the side frame, a winch 30 mounted in the vertical frame, the winch including a drive pulley mounted for vertical movement, a brake shoe mounted on one side of the winch frame, a pulley for driving the drive pulley mounted opposite the brake shoe, control means for positively moving the drive pulley up and down to selectively drive the drive pulley or apply the brake shoe to the drive pulley, a scoop 35 mounted for vertical movement with reference to the side frame and vertical frame, a cable sheave driven from the drive pulley, and a cable from the cable sheave to the scoop for raising and lowering the scoop.

LYNN JONES.
GUY BLAKE.
